UNITED STATES PATENT OFFICE.

MAURICE J. WOHL AND HARRY HERTZBERG, OF NEW YORK, N. Y., ASSIGNORS TO ECONOMY ELECTRIC COMPANY, A CORPORATION OF NEW YORK.

DESIGN FOR AN ARC-LAMP SHELL.

No. 40,036.

Specification for Design.

Patented June 8, 1909.

Application filed March 6, 1909. Serial No. 481,861. Term of patent 14 years.

To all whom it may concern:

Be it known that we, MAURICE J. WOHL and HARRY HERTZBERG, citizens of the United States, and residents, respectively, of the city of New York, borough of Manhattan, county and State of New York, and of the city of New York, borough of Brooklyn, county of Kings, and State of New York, have invented a new, original, and ornamental Design for a Shell for Arc-Lamps, of which the following is a specification, reference being had to the accompanying drawing, forming part thereof.

The figure is an elevation of an arc lamp shell, showing our new design.

The arc lamp shell comprises a cylindrical body having an ornamental outline. The upper part of the body is provided with an outwardly flaring circular portion having the upper side thereof convex and the lower side concave in cross-section, the said concave side being provided with a series of small circular openings. The central part of the body is provided with slightly raised ribs. The lower part of the body is provided with an outwardly flaring circular portion having the upper side thereof convex and the lower side concave in cross-section, the said concave side being provided with a series of small circular openings.

We claim:

The ornamental design for an arc lamp shell as shown and described.
